LEROY C. DOANE, OF MERIDEN, CONNECTICUT, ASSIGNOR TO THE MILLER COMPANY, OF MERIDEN, CONNECTICUT, A CORPORATION OF CONNECTICUT

INCLOSED LIGHTING UNIT

Application filed December 3, 1925. Serial No. 72,898.

The present invention relates to an inclosed lighting unit, and is more particularly directed toward a unit which may function as a semi-indirect lighting unit, or as a direct 5 lighting unit.

The present invention contemplates an inclosed lighting unit, having a glass top and a glass bottom, and which is provided with an interiorly arranged reflector adapted to 10 reflect most of the light upwardly or downwardly, as desired, and at the same time permit a small amount of light to reach the opposite side of the unit. In this manner one is enabled to provide a soft illumination 15 in a diffusing bowl under the reflector, when the reflector is directing the most of the light from the lower half of the lamp toward the ceiling, thereby providing an indirect lighting fixture which is illuminated on its under 20 side. It is also possible to illuminate the ceiling sufficiently to avoid shadows, when the reflector returns most of the light from the upper half of the lamp downward to increase the intensity of light in the bowl. 25 Another object of the invention is to so arrange the reflector and inclosing unit that the reflector is concealed and invisible from outside the unit even when it is illuminated.

A further object of the invention is to 30 provide a reversible reflector so that the unit may be converted at will.

The accompanying drawings show, for 35 purposes of illustration, one of the many embodiments in which the present invention 40 may take form, it being understood that the drawings are illustrative of the invention, which may be embodied in various forms.

In these drawings:

Figure 1 is a side elevational view with 45 parts in section showing the reflector below the lamp bulb in full lines and showing it inverted in dot and dash lines;

Figure 2 is an enlarged sectional view showing a detail of the construction; and

Figure 3 is an elevational view of a removable disc placed in the center of the reflector.

The lighting unit is provided with a suitable supporting stem, or the like, 10, which 50 carries any desired form of socket cover and

shade support 11. An electric lamp 12 is carried from the socket (not shown) in the usual manner, and the shade support 11 engages the lip 13 of a glass cover plate 14 so as to support the same. This cover plate, 55 as here shown, extends downwardly and outwardly so that the outside diameter is comparatively large. Its outer edge 15 is carried inside of a split channel member 16, somewhat deeper than the thickness of the 60 glass, as illustrated more clearly in Figure 2. This channel is split, as shown at 17 in Figure 1, so that it may be readily placed around the outer edge of the cover plate 14. It is not necessary to attach it to the glass. 65

A lower diffusing bowl 18 of suitable outline and design is, as here shown, mounted in a metal band 19. The lower end of this band has a channel, as shown at 20, to cooperate with the upper lip 21 of the diffusing bowl 70 18. This metal part is reenforced at its upper end by a ring 22, as indicated in Figure 2. A flat ring 23 is removably fastened to the top of the band 19 by screw 24. This ring projects inwardly, as indicated at 25, 75 so as to rest on top of the upper side of the channel 16 and supports the band 19 and diffusing bowl.

The reflecting member above referred to is here shown in the form of dished sheet 80 metal stamping 26, the central part of which is concaved downwardly, as indicated. This stamping is provided with a peripheral flange 27, which is adapted to rest on the upper side of the channel 21 of the band 19, so as to carry 85 the reflector in proper position. The reflector is provided with a downwardly reflecting surface 28 which extends from the flange 27 upwardly and inwardly, as indicated in the drawings. The stamping is then bent downwardly and is provided with a number of windows 29, separated by narrow ribs 30. These ribs serve to support the central dished 90 part of the reflector. These windows and the outer reflecting surface are so placed that some of the light coming from the lamp will pass through the windows and reach the reflecting surface 28 and be reflected downwardly into the diffusing bowl, as indicated 95 by the ray of light marked $a-a'$. In this 100

manner a small quantity of light will be permitted to reach the diffusing bowl which will glow with a dull light. The light which reaches the central part of the reflector 26 will be reflected upwardly, as indicated by the ray $b-b'$, and will pass out through the transparent plate 14 so as to illuminate the ceiling. Of course, the light falling directly on the cover plate 14 will pass through unobstructed as indicated at c . It will thus be seen that, when the reflector is in this position, most of the light will be sent upwardly and that the unit will function as a semi-indirect lighting unit. At the same time a small quantity of light will be permitted to enter the diffusing bowl and become scattered so that the bowl will not be dark from underneath.

The reflector 26 has a centrally arranged hole 31, somewhat larger than the neck of the lamp, and a removable disc 32 is held in place to close the hole by a plurality of prongs 33 resting on the reflector 26.

To convert the lamp from one in which most of the illumination is directed upwardly to one in which most of the light is directed downwardly, one removes the central disc 32 from the reflecting member, and places this member in a dot-and-dash line position of Figure 1. The flange 27 of the reflector is placed next to the outer edge 15 of the glass cover plate 14, and the split channel 16 is placed around these members so as to hold them together. A small amount of light will then pass through the windows 29 so as to reach the reflecting surface 28, as before. This light will be directed upwardly, as indicated by the rays a' and c' and dot-and-dash lines. Most of the light, however, will be reflected downwardly by the central part of the reflector, as shown by the ray marked $d-d'$ so as to illuminate the diffusing bowl 18. The unit will then act as a direct lighting unit, the ceiling being lighted to avoid shadows.

The opaque metal band 19 which surrounds the central part of the unit will effectively hide and conceal the reflector so that it will not be visible when looking at the lighted unit from the side. At all times the reflector will be invisible to the eye from underneath the lamp because of the diffusing nature of the glass. No shadows will appear on this glass when the unit is illuminated.

It is obvious that the invention may be embodied in many forms and constructions within the scope of the claims and I wish it to be understood that the particular form shown and described is but one of the many forms. Various modifications and changes being possible, I do not otherwise in any way limit myself with respect thereto.

I claim:

1. An inclosed lighting unit having a lower light-diffusing bowl, an upper glass cover,

an inclosed electric lamp, and a reversible metal reflector carried between the bowl and cover, said reflector when in one position having its reflecting surface below the lamp adapted to reflect light upwardly through the cover, and when in the other position having its reflecting surface above the lamp and adapted to reflect light downwardly to illuminate the bowl.

2. An inclosed lighting unit having a lower light-diffusing bowl, an upper glass cover, an inclosed electric lamp, and a reversible metal reflector carried between the bowl and cover, said reflector when in one position having its reflecting surface below the lamp adapted to reflect light upwardly through the cover, and when in the other position having its reflecting surface above the lamp and adapted to reflect light downwardly to illuminate the bowl, said reflector having windows permitting a portion of the light to pass through the reflector and having a second reflecting surface to reflect the light passing through said windows and redirect it in the other direction.

3. The combination with an electric lamp and a glass inclosing unit having a diffusing lower part, of a reflector carried inside the glass unit and capable of being positioned to direct most of the light upwardly or downwardly at will, means for supporting the reflector in either of the positions, there being means provided to permit a small portion of the light to be reflected in the other direction, and an opaque member for concealing the reflector.

4. An inclosed lighting unit, comprising, a downwardly opening lamp socket, a lamp in the lamp socket, a support for the lamp socket, a socket cover, a translucent glass cover plate supported from the socket cover, a sheet metal skirt supported from the periphery of the glass plate, a light-diffusing glass bowl supported from the skirt, the bowl, cover plate, and skirt enclosing the lamp, and a reflector carried between the glass parts, said reflector being shaped to reflect the most of the light toward one of the glass parts and to permit a small amount of light to reach the other glass part.

5. An inclosed lighting unit comprising, a downwardly opening lamp socket, a lamp in the lamp socket, a support for the lamp socket, a socket cover, a translucent glass cover plate supported from the socket cover, a sheet metal skirt supported from the periphery of the glass plate, a light-diffusing glass bowl supported from the skirt, the bowl, cover plate, and skirt inclosing the lamp, and a reflector carried between the glass parts, said reflector being capable of being inverted and being so shaped that, in either position, most of the light is reflected in one direction and a small amount of light is permitted to reach the glass part on the opposite side of the unit.

6. In an inclosed lighting unit, an upper glass cover, a lower bowl of diffusing glass, an inclosed electric lamp, and a sheet metal stamping supported between the cover and bowl, said stamping having a dished central portion provided with a reflecting surface adapted to reflect substantially all the light which would normally reach one of said glass parts and direct it onto the other glass part, 5 said stamping being also provided with windows outside said central portion and a peripherally arranged reflecting surface adapted to redirect light coming through the windows toward the glass part shaded by the central portion of the reflector. 10
7. In an inclosed lighting unit, an upper glass cover, a lower bowl of diffusing glass, an inclosed electric lamp, a sheet metal stamping supported between the cover and bowl, 15 said stamping having a dished central portion provided with a reflecting surface disposed in such position relative to the lamp as to reflect substantially all the light which would normally reach one of said glass parts and direct it onto the other glass part, said stamping being also provided with windows outside said central portion and a peripherally arranged reflecting surface adapted to redirect light coming through the windows 20 toward the glass part shaded by the central portion of the reflector, and mounting means whereby the reflector may be inverted. 25
8. In an inclosed lighting unit, an upper glass cover, a lower bowl of diffusing glass, 30 an inclosed electric lamp, a sheet metal stamping supported between the cover and said bowl, said stamping having a dished central portion provided with a reflecting surface adapted to reflect substantially all the light which would normally reach one of said glass parts and direct it onto the other glass part, said stamping being also provided with windows outside said central portion and a peripherally arranged reflecting surface adapted to redirect light coming through the windows 35 toward the glass part shaded by the central portion of the reflector, and a metal band between the cover and bowl and concealing the peripheral reflecting portion 40 of the stamping. 45
9. In an inclosed lighting unit, an upper glass cover, a lower bowl of diffusing glass, an inclosed electric lamp, and a sheet metal stamping supported between the cover and 50 said bowl, said stamping having a dished central portion provided with a reflecting surface adapted to reflect substantially all the light which would normally reach one of said glass parts and direct it onto the other glass part, 55 said stamping being also provided with windows outside said central portion and a peripherally arranged reflecting surface adapted to redirect light coming through the windows toward the glass part shaded by the central portion of the reflector, and a downwardly acting 60
- the bowl and stamping being sufficiently separated that, when the reflector is underneath the lamp, light from the peripheral reflecting surface may scatter and illuminate the entire bowl. 65
10. An inclosed lighting unit having a lower dish-shaped light diffusing glass part, an upper glass part of substantially the same outside diameter, an inclosed electric lamp, a reversible metal reflector of substantially the same outside diameter as the glass parts, 70 means to support the reflector in fixed position with either glass part, the reflector when mounted with the lower glass part screening the lower glass part and reflecting light toward the upper glass part, the reflector when mounted with the upper glass part being inverted and screening the upper glass part while reflecting light toward the lower glass part. 75
11. A lighting fixture comprising a pair of annular members coacting to provide a chandelier body that is open at the top and bottom, a bowl suspended from the chandelier body, a reflector within the body, means on the chandelier body for supporting said reflector, a supporting cap above said body, and a light-transmitting cover secured at its lower portion to the chandelier body and suspended from said cap whereby said body and the parts carried thereby are supported by said cover. 80
12. A lighting fixture comprising two annular members coacting to provide a chandelier body that is open at the top and bottom, a bowl suspended from the lower portion of said body, a reflector within the body, means on the chandelier body for supporting said reflector, a supporting cap above said body, and a light-transmitting cover suspended from said cap and connected to the upper portion of said body whereby said body and the parts carried thereby are supported by said cover. 85
13. A lighting fixture comprising a pair of annular members coacting to provide a chandelier body that is open at the top and bottom, a bowl suspended from the chandelier body, a reflector, means for maintaining the reflector within the chandelier body, a fixture supporting device above the chandelier body, and a light-transmitting cover attached to said supporting device and secured at its lower portion to the chandelier body whereby said body and bowl are supported by said cover. 90
14. An inclosed lighting unit having a lower light diffusing bowl, an upper glass cover, an inclosed pendant electric lamp bulb, a dished sheet metal stamping screening the lower bowl and upwardly reflecting substantially all of the light emitted in the lower hemisphere to direct it through the upper cover, the stamping having peripherally disposed windows, and a downwardly acting 95
